(No Model.)

G. W. HANNER.
RAILWAY SWITCH.

No. 518,755.

Patented Apr. 24, 1894.

Inventor

George W. Hanner
by Melvin D. Brock
Attorney

UNITED STATES PATENT OFFICE.

GEORGE W. HANNER, OF HOLBROOK, ARIZONA TERRITORY.

RAILWAY-SWITCH.

SPECIFICATION forming part of Letters Patent No. 518,755, dated April 24, 1894.

Application filed May 2, 1892. Renewed May 24, 1893. Serial No. 475,383. (No model.)

To all whom it may concern:

Be it known that I, GEORGE W. HANNER, a citizen of the United States, residing at Holbrook, in the county of Apache and Territory 5 of Arizona, have invented certain new and useful Improvements in Railway-Switches; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 represents a plan view of a section 15 of a railway track embodying my invention. Fig. 2 is a transverse vertical section thereof showing the switch-lever and its connections.

The invention consists in the following construction and combination of parts, which will 20 be first fully set forth and described and the features of novelty then pointed out in the claims.

In the drawings—A represents the main line of a track, and B the siding. The pivotal points C of the switch are connected by a switch-rod D.

E is the main hand switch-operating lever pivoted at F to a switch-stand G. This switch-stand has a slotted plate H within which the 30 lever E reciprocates, and is further provided with a pivoted locking-plate I, by means of which the switch may be set to the main line and locked in that position.

J is the main switch-operating shaft which 35 is hung in suitable bearings and hangs parallel to the main line.

K represents a series of crank-arms formed on the shaft J so as to effect a series of reciprocating or oscillating movements.

40 L represents the connecting link pivoted to the switch-lever E and to a crank-arm K on the shaft J, so as to oscillate the latter.

M is a track-lever pivoted within the track, so that under certain conditions it will lie in 45 the path of and be operated by the wheel-flanges of a train upon the main track. N is the switch-rod of this track lever M and it is connected thereto by a yielding spring-connection O, for a purpose hereinafter to be explained.

P is a plate rigidly connected to the track lever M and moving therewith.

Q is a plate pivotally connected to the plate P and having vertical ears pierced with holes in an axial line, through which passes the 55 switch-rod N, the latter having a limited end-wise play therein. This latter movement is secured by a coiled spring R surrounding the rod N and placed between the vertical ears, one end of said spring being secured to the 60 rod N, so that the spring is compressed by an outward pull of the rod N.

S is the link-rod connected to the crank K at one end and to the switch-rod D at the other.

T is another track lever rail located upon 65 the opposite side of the switch-point C on the main line and arranged to be actuated by the wheel-flanges of the car.

U is a derailing switch-rail forming a portion of the track of the siding B. V is a link-connection between the track lever T and the 70 derailing switch-rail U.

W is a link-rod connected with the lever T and rail U at one end and with a crank-arm K on the main operating-shaft J.

75 X represents the usual signal-stand of a switch, carrying a rotary signal-shaft, and signals Y thereon.

Z is the link-rod connection connecting the switch-lever E with the signal-shaft in the 80 usual manner.

It should be understood that the switch-points C, the track levers M and T, and the siding switch-rail U are all connected together and move in unison. Normally the switch is 85 set for the main line and the siding switch-rail U is set out of line with the track so that any cars which may be upon the siding, if moved by accident or design toward the main line switch—such, for instance, as the brakes 90 being accidentally let off, and the cars started by the wind or grade—will be derailed and stopped from getting onto the main line. In this position the track levers M and T are moved back from the rail and there is no contact between them and the wheels of a train passing along the main line. When however it is desired to set the switch from the main line to the siding, the hand switch-lever E is unlocked and said hand-lever pulled outwardly thereby oscillating the main shaft J and throwing the switch-points C to the siding, the siding switch-rail U in line with the track-rail and the track levers M and T out-

wardly against the inner sides of the main line rail. Provision is made against the switch-lever being locked when the switch is set for siding. In such position the passage 5 of a train along the main line will cause its wheels to act upon the track-levers M or T and throw the switch to the main line, the spring R being compressed to permit the track levers to open yieldingly, and neutralizing, in a measure, the otherwise sudden movement and shock of the moving parts.

Should by any accident the switch be left open, or remain in that position, a train approaching from either direction will strike 15 one of the track lever rails on the main line and close the switch. It is normally true to the main line.

My invention may be applied to any form of switch and the different parts may be made 20 of any suitable material and dimensions. The distances and relations of the various parts of my invention may be varied to suit the localities in which they may be placed.

I claim—

25 1. In an automatic safety railway switch, the combination of a main track, a siding, a

switch connecting the two, a switch rod therefor, a track lever pivoted within the rails of the main track, a switch-rod therefor, a spring connection between the track-lever and the 30 latter switch-rod, a second track-lever within the main track rails on the opposite side of the switch, a switch rod therefor, a car derailing switch in the siding, a rod connecting the latter switch and the track-lever, and a main 35 operating shaft along the track, the several switch rods being connected thereto for simultaneous operation.

2. In an automatic safety railway-switch, the combination of a main switch, two track 40 levers one on each side thereof, a car-derailing switch connected to one of the track-levers, and a spring switch-rod connected to the other, said switch-rods being connected for simultaneous operation.

45 In testimony whereof I affix my signature in presence of two witnesses.

GEORGE W. HANNER.
